Primary Examiner — Jack Reickel(57) **CLAIM**

The ornamental design for a display panel with animated graphical user interface, as shown and described.

DESCRIPTION

1. Display panel with animated graphical user interface

1.1 : Front

1.2 : Front

Reproduction 1.1 is a front view of the display panel with animated graphical user interface showing a first image; Reproduction 1.2 is a front view of the display panel with animated graphical user interface showing a second image. The broken line showing of a display panel with graphical user interface is included for the purpose of illustrating portions of the article and forms no part of the claimed design.

The appearance of the transitional image sequentially transitions between the images shown in Reproductions 1.1-1.2. The process or period in which one image transitions to another image forms no part of the claimed design.
